UNITED STATES PATENT OFFICE.

HERMAN F. NEHR, OF NEW YORK, N. Y.

BED.

No. 866,954.

Specification of Letters Patent.

Patented Sept. 24, 1907.

Application filed January 17, 1907. Serial No. 352,713.

To all whom it may concern:

Be it known that I, HERMAN F. NEHR, a citizen of the United States, and a resident of the city of New York, borough of Brooklyn, in the county of Kings 5 and State of New York, have invented a new and useful Improvement in Beds, of which the following is a full, clear, and exact description.

The purpose of the invention is to provide a divisional bed or a bed the spring-sustaining portion where- 10 of is in two sections removably mounted and capable of being brought together to form a double bed, or separated to constitute two single beds with a space between them, thus rendering the bed sanitary.

A further purpose of the invention is to so construct 15 a bed of the character described, that one sustaining main frame only is required to support the spring-sus- taining adjustable sections.

Another purpose of the invention is to provide legs 20 for the outer side portions of the spring-sustaining sections of the bed at the head and foot of the sections, and means for automatically folding said legs when the spring-sustaining sections are drawn inward or are closed together, and for dropping said legs to sustain- ing positions when the said sections are separated or are 25 drawn outward.

The invention consists in the novel construction and combination of the several parts as will be herein- after fully set forth and pointed out in the claims.

Reference is to be had to the accompanying drawings 30 forming a part of this specification, in which similar characters of reference indicate corresponding parts in all the figures.

Figure 1 is a perspective view of the improved bed, the sections of the body of the bed or the spring-sus- 35 taining sections being separated; Fig. 2 is a transverse section through the bed taken practically on the line 2-2 of Fig. 3, showing one spring-supporting section in normal position, and the other carried to its extreme outer position; Fig. 3 is a longitudinal vertical section 40 taken practically on the line 3-3 of Fig 2; Fig. 4 is a bottom plan view of an end of one of the body or spring-sustaining sections; Fig. 5 is a detailed vertical section 45 illustrative of controlling means for one of the auxiliary legs; and Fig. 6 is a partial transverse section taken practically on the line 6-6 of Fig. 3.

The bed consists of three prime elements, namely, a body frame A and spring supporting frames that are movable to and from each other. The body frame A consists of a head board or head section A', having 50 suitable legs 10, and a foot board or section B, also provided with suitable legs 11, together with side connecting bars 12, the latter being preferably circular in cross section. The said main frame A is also provided with channel irons 13, that are secured in any 55 suitable or approved manner to the head and foot sec-

tions A' and B at their inner faces where their legs connect with their body portions.

The spring supporting sections are designated on the drawings as C and C', being two in number. The frames for these two sections C and C' are identical and 60 consist of side bars 14 which are preferably made of angle-iron, as is illustrated, and connecting foot and end bars 15, which bars 15 are preferably of a solid character. The frame for each section C and C' is provided with an independent head board or section 16, and a 65 foot board or section 17. By preference the head board section 16 of the sliding sections C and C' of the bed are attached directly to the framings of said sliding sections and serve to support the forward or head ends of springs 18 of any desired character, which springs are 70 secured to the said head board section in any suitable or approved manner. The independent or auxiliary foot board sections 17 of the spring supporting section C and C' of the bed are by preference attached to the framings of the springs and the foot ends of the said 75 springs are sustained by brackets 19 attached to the framing of the said adjustable spring supporting sections, as is best shown in Fig. 1.

In order to facilitate the adjustment of the spring supporting sections C and C' their outer side bars 15 are preferably provided with handles 20 pivotally attached thereto. Furthermore, in order to prevent the sections C and C' from moving with undue friction, a friction roller 21 is located in the under face of each channel iron 13, adjacent to its outer end so as to engage with the end bars 15 of the said sections C and C' as said bars move in said channel irons, and furthermore, friction rollers 22 are mounted to turn in the head and the foot bars of the said spring supporting sections C and C' at their inner ends so that the rollers 22 will 90 travel upon the lower members of the channel irons 13, as is shown in Fig. 6.

The outer movement of the sliding sections C and C' is limited preferably by attaching to their inner side edges 14, downwardly extending brackets 23 that in 95 the extreme outward movement of the said spring supporting sections C and C' engage with the side members 12 of the frame A of the bed. When said spring supporting sections C and C' are carried outward it is necessary that their outward side portions should be 100 supported at the head and at the foot, and to that end lesser legs 24 are provided. When the said spring supporting sections C and C' are carried inward, these legs are automatically folded up to lie closely within the angular side portions of said sections, but when the 105 said spring supporting sections are carried outward these auxiliary legs 24 drop automatically to a sustaining position shown in Figs. 1 and 2. These movements of the auxiliary legs 24 are brought about in the following manner: Rods 25 are attached to the inner 110

faces of the outward side bars 14 of the spring supporting sections 'C and C', and these rods at their inner ends are made to pass through eyes 26 or other equivalent guides that are attached to the head and the foot members 15 of the said spring supporting sections and where the rods 25 pass through the eyes 26 they are given a crank formation, as is shown at 27 particularly in Fig. 4. Thus in operation when a spring supporting section C or C' is drawn outward the auxiliary legs 10 therefore drop by gravity as soon as their connecting rods 25 leave the side rails or rods 12 of the frame A. On the other hand, when the spring supporting sections C and C' are carried inward or in direction of each other, the rods 25 travel upon the side rails 12 of the main 15 frame or body of the bed A, are turned to a greater or less degree, and in turn carry the auxiliary legs 24 up to a folded horizontal position within the outer side rail members of the spring supporting sections C and C'. A bed constructed as has been described permits of 20 two persons sleeping in what is known as a double bed, and yet also admits of a separation of the individual springs whenever it is desired, so that in the one article I combine a double bed and two single beds which may be brought into requisition whenever desired. 25 Each spring supporting section C and C' is practically a bed within itself.

Having thus described my invention, I claim as new and desire to secure by Letters Patent,—

1. A bed comprising a main frame having head and foot 30 sections, guides carried at the inner faces of the head and foot sections, spring supporting sections mounted for lateral movement on said guides to and from each other, means for limiting the outward movement of said spring supporting sections, pivoted supports for the outward portions of the said spring supporting sections, and means for automatically folding and dropping the supports.

2. A bed comprising a main frame, channel irons secured 40 to the main frame, friction rollers located in the under face of each channel iron adjacent to its ends, and bed sections movable to and from each other in said main frame, the said sections having bars mounted to slide in said channel irons and engage the said friction rollers, the said bars being provided with friction rollers mounted to travel upon the lower members of said channel irons.

45 3. In a bed a main frame having head and foot sections, and connecting side members, channel irons secured to the inner faces of the head and foot sections, friction rollers located in the under face of each channel iron adjacent to its ends, spring supporting sections, having head and foot 50 bars and side bars, the head and foot bars being mounted to slide in said channel irons and engage the said friction rollers, the head and foot bars being provided at their

inner ends with friction rollers mounted to travel upon the lower members of said channel irons, and stops connected with the inner side bars of the said spring supporting sections and adapted to engage with the side members of the main frame for limiting the outward movement of said spring supporting sections.

55 4. In a bed, a main frame comprising a head and foot board section, and connecting side sections, spring sustaining sections having sliding and guided movement relatively to the main frame, each of said spring sustaining sections being provided with an independent head and foot board, auxiliary legs for supporting the outward portions of the spring sustaining sections, and means for automatically raising and lowering the said legs as the sections are moved inward or outward.

60 5. In a bed, a main frame comprising head and foot sections, and connecting side members, and channel irons secured to the inner faces of the foot and head sections, spring sustaining sections mounted to slide in the said channel irons, each spring sustaining section being provided with an independent head and foot portion, legs pivotally connected with the spring sustaining sections, and means for automatically dropping and raising the said legs to a folded position as the said spring sustaining sections are manipulated.

65 70 6. In a bed or similar article, the combination with a main frame comprising end members and connecting side members, of a supporting object slidably mounted in the said frame, legs pivotally attached to the said slidably object, rods attached to the said legs, and pivotally attached to the end portions of the said slidably objects, the said rods at their latter point of attachment being provided with crank terminals, the said rods being adapted in the 75 movements of the slidably objects, to engage with the side members of the main carrying frame.

7. In a bed, a main frame comprising head and foot sections and connecting side members, guides on the inner faces of the foot and head sections, spring sustaining sections mounted to slide on said guides, each spring sustaining section being provided with an independent head and foot portion, legs pivotally connected with the spring sustaining sections, and means connected with said legs and said sections for automatically dropping and raising said 80 legs when the sections are manipulated.

8. A bed comprising a main frame, spring supporting sections mounted in the said main frame for lateral movement to and from each other, legs pivotally attached to said spring supporting sections, and means for moving said 90 legs when the sections are manipulated, the said means comprising rods attached to said legs and pivotally connected with the end portions of said spring supporting sections.

95 100 In testimony whereof I have signed my name to this 105 specification in the presence of two subscribing witnesses.

HERMAN F. NEIR.
